CLAIM

The ornamental design for a stackable medication cup, as shown and described.

DESCRIPTION

FIG. 1 shows a perspective view of a stackable medication cup.

FIG. 2 shows a front view of the stackable medication cup.

FIG. 3 shows a rear view of the stackable medication cup.

FIG. 4 shows a top plan view of the stackable medication cup.

FIG. 5 shows a bottom plan view of the stackable medication cup.

FIG. 6 shows a right side view of the stackable medication cup; and,

FIG. 7 shows a left side view of the stackable medication cup.

The shade lines in the Figures show contour and not surface ornamentation.

1 Claim, 4 Drawing Sheets
